(57) **CLAIM**

The ornamental design for a mobile printer, as shown and described.

DESCRIPTION

FIG. 1 is a front, bottom, and right side perspective view of a mobile printer;

FIG. 2 is a rear, top, and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The evenly spaced broken lines shown in the figures are for the purpose of illustrating portions of the mobile printer that form no part of the claimed design. The dot-dash broken lines in the figures show an unclaimed boundary of the claimed design.
